PHOTOGRAPHIC CONTACT-PRINTING APPARATUS

Lodewijk Evert van der Grinten, Venlo, Netherlands, assignor, by mesne assignments, to Chemische Fabriek L. van der Grinten N. V., Venlo, Netherlands, a corporation of the Netherlands

Application July 19, 1950, Serial No. 174,665

Claims priority, application Netherlands
July 21, 1949

19 Claims. (Cl. 95—77.5)

1

The invention relates to a type of photographic contact-printing apparatus comprising a panel of translucent material curved in one direction, thus having straight generating lines on its surface, co-operating on its convex side (which may be termed a "straight convex" surface) with a flexible applying apron for applying and pressing the material to be exposed onto the panel under tension, and members engaging the feeding apron in a direction transverse to the generating lines of the panel in order to hold the apron under tension. Exposure apparatus of this type, as thus far described, is known.

With none of the known apparatus, provided with a curved panel and a flexible applying apron, is it possible to copy from books in the sense that a page from a book can be placed between the panel and the apron in the printing position without the said page first being removed, i. e. torn, from the book. In none of the known apparatus is there sufficient space or opportunity for accommodating the rest of the book during the printing of said single page from it and even if, with the greatest difficulty, accommodation can be provided for the rest of the book, this involves a considerable deformation of the book, which is undesirable. Moreover it is even then not possible to copy the page far into the fold of the book, so that with the known apparatus only thin periodicals can be dealt with, and these only when they are printed with a wide margin.

The present invention is concerned with an improved form of apparatus which overcomes these difficulties. According to the present invention photographic contact-printing apparatus comprises a linearly curved exposure panel of light-transmitting material, adapted to be illuminated from the concave side thereof, an apron adapted to be laid close to the convex side of said panel and to sandwich between itself and the panel a sheet of light-sensitive material and an original sheet to be copied, the said apron terminating in a thin flat edge along a line parallel to the generating lines of the panel, means for moving the apron and panel relatively from a rest position in which they are apart to a working position in which the apron lies close to the panel, and vice versa, such that in the said working position the said terminal edge lies against the panel, and means holding the said apron under tension in a direction perpendicular to the generating lines of the panel said tension means consisting of members pulling the said terminal edge in the direction of the extension of the apron beyond said edge or members secured

2

to the face of the apron more remote from the panel and pushing the said edge in the said direction.

The invention will now be described with reference to the accompanying diagrammatic drawings which illustrate simple apparatus and also apparatus including preferred features of the invention.

Figs. 1 and 2 illustrate an apparatus for copying pages from books in the resting and the working positions respectively.

Figs. 3 and 4 similarly illustrate an alternative apparatus for the same purpose.

Fig. 5 illustrates a form of apparatus embodying a flexible apron.

Fig. 6 illustrates a modified form of the apparatus according to Figs. 1 and 2.

Figs. 7 and 8 illustrate a further alternative apparatus, again in the resting and the working positions respectively.

Figs. 9 and 10 illustrate in the resting and working positions respectively, apparatus embodying a moving panel.

Referring to Fig. 1 a tube-shaped lamp 1 is located within a curved panel 2 (in this case a full-circle cylinder, mounted so as to be rotatable about its axis by means of members not illustrated). An applying apron 3 ends on the left in a flat and thin terminal edge 4. This terminal edge 4 is stiffened by means of a flat, straight steel rib extending on either side beyond the apron and to these extensions are secured tape 5. The other end of the apron lies against the cylinder 2 at the position 6 and this end also has an extension to which two tapes 7, provided on either side of the apron and forming a continuation of the apron, are attached, these tapes 7 being looped about the cylinder and passing underneath the cylinder to the right. The tapes 5 are laid over two pulleys 8 and the tapes 7 over two pulleys 9. Below the apparatus these tapes are interconnected by means of two springs 10 (for the loop construction thus obtained reference may be made to copending application Ser. 761,314).

The apron 3 with its edge 4 can be moved to the right and back again; when this is done, the apron will wind and unwind itself about the cylinder 2. Thus, the loop construction with the spring 10 described above will keep the apron parallel to the axis of the cylinder 2 in every position.

In Figs. 1 and 2 a book has been illustrated (in Fig. 1 in the resting position and in Fig. 2 in the working position), the page to be copied being designated by 11; while the photosensitive ma-

3

terial on which a reflex copy of the said page is to be produced is designated by 12. The book is supported by a slide 13 mounted flexibly on wheels 14 which are capable of running backwards and forwards on rails 15. When the slide 13 is moved to the right on the rails 15, the apparatus reaches the position illustrated in Fig. 2. The page of the book to be copied and the superposed photo-sensitive material are carried along between the cylinder 2 and feeding apron 3, and pressed closely together as necessary for contact-printing. After the exposure the apparatus is returned to the resting position of Fig. 1; the light sensitive material on which the reflex copy of the page 11 has been reproduced is removed, a fresh page is put in readiness on the feeding apron 3 over the terminal edge 4, fresh light-sensitive material is laid over the page and the apparatus is again moved into the working position shown in Fig. 2. These operations may be repeated for successive pages and the apparatus thus provides a simple method for copying pages from books without the book itself having to be subjected to inconvenient pressure or other forces. As a result the books are not seriously deformed or damaged.

With some books it is difficult to reach the "fold" or spine even using an apparatus to Figs. 1 and 2; and a preferred form of the invention by means of which the fold can be reached more effectively is obtained by arranging that the position of the apron on the curved panel is such that in the working position the terminal edge of the apron coincides with a free edge of the panel on one of its generating lines, i. e. so that the said terminal edge of the apron registers with the free edge of the panel as accurately as possible. A simple embodiment of such apparatus is illustrated in Figs. 3 and 4, which again show the resting and the working positions respectively.

Referring to Figs. 3 and 4, the apparatus comprises a curved panel 2a, apron 3a having a terminal edge 4a, a holder or ledge 13a for the book, a support 16 for the back of the book. The drawings show the page 11 to be copied and the photo-sensitive material 12. The panel 2a has a fixed position in the apparatus and is fixed relative to the shaft 17, located about as indicated in Fig. 3, around which the holder 13a is moved into the working position, illustrated in Fig. 4, with the aid of the handle 34. Then the free edge 18 of the panel will coincide accurately with the edge 4a of the apron 3a, while the part of the book projecting to the left remains free, as illustrated. In this way the edges 18 and 4a can enter far into the fold of the book, so that it becomes possible to copy the parts printed near this fold. The apron 3a and its terminal edge 4a are kept parallel to the panel in essentially the same manner as with the apparatus according to Figs. 1 and 2, by means of the two springs 16a engaging the terminal edge 4a on either side of the apron near said terminal edge. At the other end the apron is fastened at 17. The stiffening of the terminal edge 4a may project, just as in the apparatus according to Figs. 1 and 2, on either side of the free terminal edge, and these projections may be freely supported in the holder 13a. In Figs. 3 and 4 these supports have been omitted for the sake of clearness. When the apparatus is in the working position, a source of light may be provided or the apparatus may be moved towards a source of light or be exposed, for example, to sunlight.

4

Fig. 5 illustrates diagrammatically that a curved exposure panel 2b can move up and down in the direction of the arrows 19 and 20. The apron 3b is flexible in this case (made, for example, of rubber) and fastened at 21 over its full width. When the panel 2b moves in the direction of arrow 20, the free edge 18b of the panel will meet the terminal edge 4b of the apron as accurately as possible. Located in this terminal edge 4b is the end of the supporting plate 22, which is fixed in the apparatus. This supporting plate 22 thus acts as a pushing member on the terminal edge 4b and gives a fixed position to this terminal edge 4b in the apparatus.

The construction with a pushing member in the form of a plate ending in the terminal edge of the apron has been found to be particularly efficient. A form of apparatus according to the invention using such a pushing plate is illustrated diagrammatically in Fig. 6. The apron 3c and the two side tapes 7c form a loop about the cylinder 2c in the manner described in the U. S. application Ser. No. 761,314, in the same general manner as in the apparatus of Figs. 1 and 2. The tapes 7c are passed downwards over the pulleys 24 running on shafts which are connected to the plate 22c by means of the supports 25. The whole of the loop comprising the apron 3c and the tapes 7c is kept under tension by the spring 16c, which is fastened at 23 to the bottom of the plate 22c. Just as in the apparatus of Figs. 1 and 2, the cylinder 2c is rotatable about the fixed shaft. When the plate 22c is moved to the right, the apron 3c winds itself onto the cylinder 2c, and the apparatus thus reaches the working position, in which working position the terminal edge 4c will touch the lowest generating line of the cylinder. On this terminal edge 4c a book with the page to be copied and the superposed light-sensitive material may be placed, in exactly the same way as with the apparatus described above. The pushing plate 22c in this apparatus has the additional useful function of constituting a kind of table with the apron placed upon it, so that the said apron is supported, which facilitates placing and positioning the book while the apparatus is in the resting position. In Fig. 6 neither the means with which the plate 22c is kept parallel to itself during the movement, nor the supports required for carrying the book, have been illustrated but these means may have the same construction as those of Figs. 1 and 2.

Apparatus employing a panel in the form of a cylinder, as illustrated in Figs. 1, 2 and 6, presents the advantage of high efficiency during exposure, if—as is technically possible—a tube lamp is used as the source of light 1. On the other hand, as will be apparent from Figs. 3, 4 and 5, the registration of an edge of the panel with the terminal edge of the apron presents important advantages when copying pages from books. In Figs. 7 and 8 (which illustrate the resting and working positions respectively) an apparatus is illustrated diagrammatically with which both advantages are obtained.

Referring to Figs. 7 and 8 the cylinder 2d is interrupted, as illustrated, by a slot which is filled up by a recessed cap 27, the cylinder thus having an edge extending on a generating line. In this apparatus the apron 3d, as illustrated, is not extended with the aid of tapes looped about the cylinder, as in the apparatus of Figs. 1, 2 and 6, but it is passed outside the cylinder over the pulleys 26, the pulley 24d, the spring 16d,

and the support 23d, in the manner of Fig. 6. Its other end terminates in the flat edge 4d.

In the resting position of Fig. 7 a book with a page 11 and light-sensitive material 12 may be introduced as diagrammatically illustrated and as indicated in Figs. 1 and 2.

Fig. 8 illustrates the working position, which is reached by shifting to the right the plate 22d with the terminal edge 4d, of the apron 3d, while the registration of the edge 18d of the cylinder with the terminal edge 4d of the apron makes it possible to reach the fold of the book, as illustrated.

Figs. 9 and 10 illustrate an apparatus in which, in passing from the resting position (Fig. 9) to the working position (Fig. 10), neither the terminal edge 4e nor the book placed in the apparatus need be displaced. The book may, of course, be supported as above, for example, with a support 16 as in Figs. 3 and 4.

Referring to Figs. 9 and 10, the apparatus includes a table 28 and an exposure casing 29 with reflector. The apron is fastened to the panel or to the structure supporting the said panel at 39. Two flexible tension members 31 provided on either side of the apron are fastened at 35 to the panel or casing, pass along the outside of the curved panel or the corresponding part of the exposure casing towards the back of the plate 22e, where they pass over pulleys 24e, in the manner of Fig. 6, and are tightened by means of the springs 10e fixed to 23e. These flexible tension members 31 thus cross the apron and run onto and off the curved panel in the reverse direction to the apron itself. This device keeps the feeding apron 3d under constant tension, on the one hand via the plate 22e and on the other hand via the panel system. A handle 32 for the exposure casing is provided and the plate 22e is supported by the supports 33 and connected to the table 28. The supports leave the bottom surface of the plate 22e substantially free. The plate 22e engages the thin flat terminal edge 4e of the apron 3e. Thus, the tension member acting on the terminal edge again constitute a plate-shaped pushing member, although the tension is ultimately produced by the spring 10e. In moving from the resting position to the working position, the exposure casing 29 is transferred by means of the handle 32 from the position of Fig. 9 to the position of Fig. 10 and kept in the latter position, and all the conditions required for the contact-printing are then fulfilled.

What I claim is:

1. In a contact photoprinting apparatus, a curved light-pervious exposure panel having an outer surface convex in one direction and straight in the transverse direction, a flexible apron held to said surface, the panel and apron being relatively movable between a loading position in which a portion of the apron extends away from said surface in a plane tangential thereto to receive sheet material laid over such portion and an exposing position in which such portion holds the material wrapped against said surface, a thin flat and stiff terminal edge on an end of said apron portion and means constantly holding said edge substantially parallel to generating lines on said surface and in said tangential plane, and means continuously holding the apron stretched between said terminal edge and the panel so that the apron extends tangentially from said surface to said edge in a flat plane in the loading position of the panel and apron, said terminal edge being held free of obstructions in

said loading position so that it enters readily into the fold of an open book placed thereagainst, said surface terminating at a free edge of the panel on one of its generating lines, said free panel edge substantially coinciding with said terminal edge in said exposing position and being bordered by unobstructed space accommodating a bulge of the open book.

2. An apparatus as described in claim 1, said 10 panel being in the form of a cylinder having a recessed circumferential area forming said unobstructed space.

3. In a contact photoprinting apparatus, a 15 curved light-pervious exposure panel having an outer surface convex in one direction and straight in the transverse direction, a flexible apron held to said surface and movable relative to it in a path transverse to its generating lines between a loading position in which a portion of the 20 apron extends straight from said surface to receive sheet material laid thereover and an exposing position in which said portion holds the material wrapped against said surface, a thin flat stiff terminal edge on the end of said apron 25 portion and substantially parallel to said generating lines, means continuously holding the apron stretched between said terminal edge and the panel and holding said terminal edge unobstructed in loading position so that said edge enters readily into the fold of an open book placed thereagainst, and a movable carrier underlying said edge to support such book, the carrier being 30 movable along said path with said terminal edge.

4. An apparatus as described in claim 3, the 35 path of said apron portion being substantially tangent to said surface, and a trackway substantially parallel to said path for supporting said carrier.

5. In a contact photoprinting apparatus, a 40 cylindrically curved light-pervious exposure panel mounted for rotation about its axis, a flexible apron held to the convex surface of the panel and movable with panel rotation in a path transverse to said axis between a loading position in 45 which a portion of the apron extends tangentially from said surface to receive sheet material to be exposed and an exposing position in which such portion holds the material wrapped against said surface, and a reciprocable work support 50 presenting a substantially flat working surface movable below the panel in a path substantially tangent to the panel surface, said apron portion terminating at the forward end of said working surface and forming therewith a thin stiff terminal edge parallel to said axis for insertion into the fold of an open book placed thereagainst.

6. In a contact photoprinting apparatus, a 55 cylindrically curved light-pervious exposure panel mounted for rotation about its axis, a flexible apron held to the convex surface of the panel and movable with panel rotation in a path transverse to said axis between a loading position in which a portion of the apron extends tangentially from said surface to receive sheet material to be exposed and an exposing position in which such portion holds the material wrapped against said surface, and a reciprocable work support 60 presenting a substantially flat working surface movable below the panel in a path substantially tangent to the panel surface, said apron portion terminating at the forward end of said working surface and forming therewith a thin stiff terminal edge parallel to said axis for insertion into the fold of an open book placed thereagainst, and 65 tensioning means interconnecting the panel and

a backward part of said support so as to hold the apron in a stretched condition.

7. An apparatus as described in claim 6, said tensioning means including spaced elongated flexible members disposed on either side of the apron and extending from the panel surface to a backward part of said work support.

8. An apparatus as described in claim 6, said tensioning means including spaced elongated flexible members disposed on either side of the apron and extending from the panel surface to a backward part of said work support, the apron and said flexible members having interconnected end portions to form a continuous band, the band being looped about the panel with the apron and said members crossing each other at and extending in opposite directions from the point of tangency of said working surface.

9. An apparatus as described in claim 6, said work support comprising a book holder spaced below said terminal edge.

10. In a contact photoprinting apparatus comprising a curved light-pervious panel having an outer surface convex in one direction and straight in the transverse direction, a light source at the concave side of said panel and a flexible apron for applying sheet material to said surface for exposure through said panel, the panel and apron being relatively movable between a loading position in which a portion of the apron ending in a transverse terminal edge extends away from said surface in a plane tangential thereto to receive such material laid over such portion and an exposing position in which such portion is wrapped against said surface to hold such material thereagainst, stiffening means rendering said terminal edge substantially flat, thin and rigid, means supporting the stiffened terminal edge in said tangential plane in a position free from obstructions and substantially parallel to the generating lines of said surface, so that said edge can enter readily into the fold of an open book placed thereagainst when the panel and apron are in loading position, and means continuously applying longitudinal tension to the apron up to said stiffened terminal edge so that said apron portion is stretched flat up to said edge in said loading position and sandwiches sheet material laid over such portion tightly against said surface as the panel and apron are relatively moved to exposing position.

11. In a contact photoprinting apparatus comprising a curved light-pervious panel having an outer surface convex in one direction and straight in the transverse direction, a light source at the concave side of said panel and a flexible apron for applying sheet material to said surface for exposure through said panel, the panel and apron being relatively movable between a loading position in which a portion of the apron ending in a transverse terminal edge extends away from said surface in a plane tangential thereto to receive such material laid over such portion and an exposing position in which such portion is wrapped against said surface to hold such material thereagainst, stiffening means rendering said terminal edge substantially flat, thin and rigid, means supporting the stiffened terminal edge in said tangential plane in a position free from obstructions and substantially parallel to the generating lines of said surface, so that said edge can enter readily into the fold of an open book placed thereagainst when the panel and apron are in loading position, and means continuously applying longitudinal tension to the

75 apron up to said stiffened terminal edge so that said apron portion is stretched flat up to said edge in said loading position and sandwiches sheet material laid over such portion tightly against said surface as the panel and apron are relatively moved to exposing position, said panel presenting a free edge substantially parallel to said generating lines and substantially coinciding with said terminal edge in said exposing position.

12. An apparatus as described in claim 10, said supporting means holding said stiffened terminal edge in a relatively fixed position and said panel and said supporting means being relatively movable bodily to establish said loading and exposing positions.

13. An apparatus as described in claim 10, said supporting means holding said stiffened terminal edge in a relatively fixed position and said panel and said supporting means being relatively movable bodily to establish said loading and exposing positions, said panel presenting a free edge substantially parallel to said generating lines and substantially coinciding with said terminal edge in said exposing position.

14. In a contact photoprinting apparatus comprising a curved light-pervious panel having an outer surface convex in one direction and straight in the transverse direction, a light source at the concave side of said panel and a flexible apron for applying sheet material to said surface for exposure through said panel, the panel and apron being relatively movable between a loading position in which a portion of the apron ending in a transverse terminal edge extends away from said surface in a plane tangential thereto to receive such material laid over such portion and an exposing position in which such portion is wrapped against said surface to hold such material thereagainst, stiffening means rendering said terminal edge substantially flat, thin and rigid, means supporting the stiffened terminal edge in said tangential plane in a position free from obstructions and substantially parallel to the generating lines of said surface, so that said edge can enter readily into the fold of an open book placed thereagainst when the panel and apron are in loading position, and means continuously applying longitudinal tension to the apron up to said stiffened terminal edge so that said apron portion is stretched flat up to said edge in said loading position and sandwiches sheet material laid over such portion tightly against said surface as the panel and apron are relatively moved to exposing position, there being a rigid plate underlying said panel and said apron and presenting across its forward end a thin rigid edge engaging said terminal edge of the apron so as to constitute said supporting means and said stiffening means.

15. In a contact photoprinting apparatus comprising a curved light-pervious panel having an outer surface convex in one direction and straight in the transverse direction, a light source at the concave side of said panel and a flexible apron for applying sheet material to said surface for exposure through said panel, the panel and apron being relatively movable between a loading position in which a portion of the apron ending in a transverse terminal edge lies away from said surface to receive such material laid thereover and an exposing position in which such portion is wrapped against said surface to hold such material thereagainst, stiffening means rendering said terminal edge substantially flat, thin and

rigid and means supporting the stiffened terminal edge in a position free from obstructions and substantially parallel to the generating lines of said surface, so that said edge can enter readily into the fold of an open book placed thereagainst when the panel and apron are in loading position, and means continuously applying longitudinal tension to the apron up to said stiffened terminal edge so that said apron portion is stretched in a flat plane up to said edge in said loading position and sandwiches sheet material laid over such portion tightly against said surface as the panel and apron are relatively moved to exposing position, there being a rigid plate underlying said panel and said apron and presenting across its forward end a thin rigid edge engaging said terminal edge of the apron so as to constitute said supporting means and said stiffening means, said tension applying means comprising flexible members stretched between said panel and a backward part of said plate.

16. In a contact photoprinting apparatus comprising a curved light-pervious panel having an outer surface convex in one direction and straight in the transverse direction, a light source at the concave side of said panel and a flexible apron for applying sheet material to said surface for exposure through said panel, the panel and apron being relatively movable between a loading position in which a portion of the apron ending in a transverse terminal edge extends away from said surface in a plane tangential thereto to receive such material laid over such portion and an exposing position in which such portion is wrapped against said surface to hold such material thereagainst, a rigid plate underlying said panel and said apron and having across its forward end a thin rigid edge engaging said terminal edge of the apron, said thin rigid edge rendering said terminal edge substantially flat, thin and rigid and holding it in said tangential plane in a relatively fixed position substantially parallel to the generating lines of said surface, means supporting said plate so that it holds said terminal edge free from obstructions when the panel and apron are in said loading position, and means extending from a backward part of said plate for continuously applying longitudinal tension to the apron up to said terminal edge so that said apron portion is stretched flat up to said edge in said loading position and sandwiches sheet material laid over such portion tightly against said surface as the panel and apron are relatively moved to exposing position.

17. In a contact photoprinting apparatus comprising a curved light-pervious panel having an outer surface convex in one direction and straight in the transverse direction, a light source at the concave side of said panel and a flexible apron for applying sheet material to said surface for exposure through said panel, the panel and apron being relatively movable between a loading position in which a portion of the apron ending in a transverse terminal edge extends away from said surface in a plane tangential thereto to receive such material laid over such portion and an exposing position in which such portion is wrapped against said surface to hold such material thereagainst, a rigid plate underlying said panel and said apron and having across its forward end a

thin rigid edge engaging said terminal edge of the apron, said thin rigid edge rendering said terminal edge substantially flat, thin and rigid and holding it in said tangential plane in a relatively fixed position substantially parallel to the generating lines of said surface, means supporting said plate so that it holds said terminal edge free from obstructions when the panel and apron are in said loading position, and means extending from a backward part of said plate for continuously applying longitudinal tension to the apron up to said terminal edge so that said apron portion is stretched flat up to said edge in said loading position and sandwiches sheet material laid over such portion tightly against said surface as the panel and apron are relatively moved to exposing position, said panel presenting a free edge substantially parallel to said generating lines and substantially coinciding with said terminal edge in said exposing position.

18. In a contact photoprinting apparatus, a curved light-pervious panel having a convex outer surface which is straight in transverse direction and extends in an arc of less than 360° between opposite end edges of the panel, a light source at the concave side of said panel, a flexible apron held to said panel and arranged to extend from one of said end edges over said surface to a transverse terminal edge of the apron, said panel and said apron being relatively movable between a loading position in which the apron extends tangentially away from said surface to receive sheet material laid thereon for exposure and an exposing position in which the apron is wrapped against said surface to hold such material thereagainst, a rigid plate underlying said panel and said apron and having across its forward end a thin rigid edge engaging said terminal edge of the apron, said thin rigid edge rendering said terminal edge substantially flat, thin and rigid and holding it in a relatively fixed position substantially parallel to the generating lines of said surface, the other of said end edges of the panel substantially coinciding with said terminal edge in said exposing position, and means extending to said surface from a backward part of said plate for continuously applying tension to the apron so as to keep it stretched longitudinally up to said terminal edge.

19. An apparatus as described in claim 18, said tension applying means including spaced elongated flexible members disposed on either side of the apron and crossing the apron approximately at its point of tangency to said surface.
